ADJUSTABLE MOUNT FOR LIGHTING FIXTURES

Leonard Atkin, Springfield, N.J., assignor to Stone Manufacturing Co., a corporation of New Jersey

Filed Aug. 25, 1959, Ser. No. 57,304

Term of patent 14 years

(Cl. D48—4)

FIG.1

FIG.2

FIG.3

FIG.4

FIG.5

Figure 1 is a side elevational view of an adjustable mount for lighting fixtures, showing my new design;

Figure 2 is a front elevation view thereof;

Figure 3 is a rear elevational view thereof;

Figure 4 is a top plan view thereof; and

Figure 5 is a bottom plan view thereof.

I claim:

The ornamental design for an adjustable mount for lighting fixtures, substantially as shown.
